UNITED STATES PATENT OFFICE.

WILLIAM T. JONES, OF DETROIT, MICHIGAN, ASSIGNOR TO THE EDMUNDS & JONES MFG. CO., OF DETROIT, MICHIGAN, A CORPORATION OF MICHIGAN.

LENS AND REFLECTOR RETAINER FOR LAMP-DOORS.

1,045,852.

Specification of Letters Patent.

Patented Dec. 3, 1912.

Application filed September 11, 1911. Serial No. 648,752.

To all whom it may concern:

Be it known that I, WILLIAM T. JONES, a citizen of the United States, residing at Detroit, in the county of Wayne, State of Michigan, have invented certain new and useful Improvements in Lens and Reflector Retainers for Lamp-Doors; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to a lens and reflector retainer for the doors of vehicle lamps and consists in the construction and arrangement of parts hereinafter more fully set forth and claimed.

The object of the invention is to provide simple and efficient means for securing a lens in the door of a vehicle lamp in a manner to prevent rattling thereof and obviate the liability of breakage and at the same time provide for retaining in position upon said door a reflector in which a burner is located, the arrangement being such as to retain both the glass and reflector in place by the same fastening means, and at the same time exclude dust from the interior of the reflector whereby the necessity of cleaning its polished surface is obviated. The arrangement comprehends such an association of parts as to enable the reflector to be easily and quickly secured in place and readily removed when desired.

The above object is attained by the structure illustrated in the accompanying drawings, in which:

Figure 1 is a view showing the inner face of the door of a lamp and illustrating the application of my invention thereto, the body of the lamp being broken away. Fig. 2 is a horizontal section through the door, the lens, and the reflector. Fig. 3 is an enlarged fragmentary view in section through the marginal portion of the reflector, showing a compressible buffer seated in a channel formed therein.

Referring to the characters by reference, 1 designates a lamp body to which is hinged in any suitable manner a door 2, which is preferably circular in form and adapted to open outwardly from the body of the lamp.

The outer face of the door is provided with a rolled flange 3, the edge of which forms an annular shoulder against which the lens 4 is adapted to rest.

At the inner edge of the door frame the metal thereof is rolled inwardly so as to form an inwardly facing shoulder 5 which is off-set somewhat from the wall of said frame. A parabolic reflector 6 is employed of suitable metal whose inner face is polished, and which at the vertex thereof is provided with a suitable burner 7 illustrated herein as an electric burner. At the outer end of the reflector it is provided with an outwardly extending circular flange 8 of a diameter to lie within the circular frame of the door. Formed in the flange 8 of the reflector is a circular channel 9, the side walls of which are normally straight, and in which is seated a ring 10 of rubber or other compressible material. To secure said ring in the channel 9 one side of said channel is forced inwardly after the ring is disposed therein, as clearly shown in Fig. 3, whereby the transverse area of said channel is reduced at or near the open side thereof so as to retain the compressible filling 10 therein. Said ring or filling is of greater width than the depth of said channel so that a portion of said ring projects 85 from the channel beyond the outer face of the flange 8. When the reflector is in position within the door of the lamp the projecting portion of the ring 10 bears against the inner face of the glass and holds said 90 glass against the shoulder formed by the rolled outer portion 3 of the door of the lamp.

To detachably retain the reflector and glass within the door a spring ring 12 is employed. Said ring is open and the terminals 13 thereof are bent outwardly so as to engage under the annular shoulder 5 of the door frame. The radius of the circle described by the ring 12 is slightly greater than that of the flange 8 of the reflector so as to enable said flange to pass through said ring when the latter is in position in the door of the lamp. In order that the ring 12 may have a bearing upon the inner face 100 of the flange of the reflector to hold said reflector in the door of the lamp, and at the same time have a bearing upon the annular shoulder 5 of the door frame to hold the reflector and glass therein, said ring is pro- 110

vided with a series of inwardly extending bends or points 14 and a series of interposed outwardly extending bends or points 15. The bends 14 are adapted to engage the outer face of the marginal portion of the flange 8 to hold the reflector in place while the outwardly extending bends 15 together with the outwardly turned points 13 of the terminals of said ring engage under the annular shoulder 5. To provide the ring with sufficient transverse flexibility to hold said parts within the frame of the lamp door under the requisite tension said ring is provided with a series of lateral bends in opposite directions in alternate succession as shown by dotted lines in Fig. 2, the angle of said lateral bends being located at the points where the short inwardly and outwardly extending bends 14 and 15 occur. By this arrangement the inwardly bent points 14 are caused to forcibly bear upon the inner face of the flange 18 of the reflector, while the outwardly bent points 15 together with the terminals 13 of said ring bear forcibly against the annular shoulder 5 so that the rubber ring in the flange of the reflector is held with such tension against the inner face of the glass as to force the outer face of said glass against the rolled shoulder 3. This arrangement not only securely fastens the reflector and glass in the door frame of the lamp but also serves to exclude dust and moisture from the interior of the reflector by reason of the sealing action of the rubber ring against the face of the glass or lens.

In order to enable the reflector to be removed from the door frame and re-inserted therein when the ring 12 is in position the circular margin of the flange 8 of said reflector is provided with a plurality of curved notches or recesses 16, as clearly shown in Fig. 1. These recesses are so disposed as to register with the inwardly bent points 14 of the ring 12, so that, by so placing the reflector as to cause said recesses to receive said points, and partially rotating the reflector in either direction, the points 14 will be caused to ride onto the solid portion of the flange 8 out of said recesses and firmly lock the reflector and glass in the door frame under such tension as to obviate rattling of the parts.

The burner 7 being fixed in the vertex of the reflector by a lock nut 17 is perfectly held in focus in a manner that requires no adjusting and obviates the possibility of any change in the relations between the reflector and burner.

Having thus fully set forth my invention, what I claim as new and desire to secure by Letters Patent is:—

1. In combination with a lamp frame, a lens bearing with its outer face against a portion of said frame, a reflector in the rear

of said lens, and means interposed between a portion of the lamp frame and said reflector for yieldingly retaining the reflector and lens in position in the door.

2. A lamp frame having an annular retaining member, a glass seated against said member, a reflector in the rear of said glass, a compressible element interposed between the glass and reflector to transmit pressure from the latter to the former, and a yieldable locking member coöperating with the reflector and with the frame of the lamp for retaining the reflector and glass in place. 75

3. A lamp door having a retaining member, a glass lying against said member, a reflector in the rear of the glass having a marginal portion that bears upon the rear face thereof, the door frame having a shoulder in the rear of the marginal portion of said reflector, and a yieldable locking member 85 interposed between said shoulder and the margin of said reflector.

4. A lamp door having a retaining member, a glass lying against said retaining member, a reflector having a marginal flange 90 lying against the rear face of said glass, the door frame having a shoulder in the rear of the flange of the reflector, and a spring locking ring interposed between the margin of said reflector and said shoulder on the door 95 frame and coöperating therewith to lock the reflector and glass in position.

5. A lamp door having a retaining member, a glass lying against said member, a reflector having a marginal flange lying 100 against the rear face of said glass, the door frame having a projecting shoulder, locking means coöperating with said shoulder and the reflector to lock the reflector and glass in the door frame, and means for excluding 105 dust from between the marginal flange of the reflector and the inner face of the glass.

6. A lamp door having a supporting member, a glass lying thereagainst, a reflector mounted upon the rear face of said glass, 110 and resilient means for urging the reflector and glass against said supporting member to yieldingly retain the glass and reflector within the frame of the door.

7. A lamp door having a retaining member, a glass lying against said member, a reflector having a marginal flange, a compressible element between the flange of the reflector and the rear face of the glass, and means for applying a yielding pressure to 120 the rear face of the flange of the reflector to crowd the compressible element against the glass and hold the glass against the retaining member of the door.

8. A lamp door having a retaining member, a glass lying against said member, a reflector having a marginal flange provided with a channel therein, a compressible element lying in said channel and adapted to engage the rear face of the glass, and means 125 130

cooperating with the flange of the reflector and the door frame for locking said parts in position.

9. A lamp door having a retaining member, a glass lying against said member, a reflector having a marginal flange engaging the rear face of said glass, a shoulder on the door frame, and a spring ring having lateral bends therein and contact points at said bends adapted to engage said shoulder of the door frame and the margin of said reflector, when said ring is interposed between the margin of the reflector and said shoulder, to yieldingly retain the parts in position.
10. A door frame having a retaining member, a glass lying against said member, a

reflector having a marginal flange lying against the rear face of said glass, the door frame having an annular shoulder in the rear of the flange of the reflector, a spring ring having projecting points adapted to engage said shoulder and said flange to retain the reflector and glass in the door frame, and the flange of the reflector having notches adapted to register with the inward projecting points on said ring.

In testimony whereof, I sign this specification in the presence of two witnesses.

WILLIAM T. JONES.
